UNITED STATES PATENT OFFICE.

WILLIAM C. STEWART, OF LYNN, MASSACHUSETTS, ASSIGNOR TO MANUFACTURERS MACHINE COMPANY, OF MONTCLAIR, NEW JERSEY, A CORPORATION OF NEW JERSEY.

BOOT AND SHOE SOLE.

No. 871,968.

Specification of Letters Patent.

Patented Nov. 26, 1907.

Application filed November 22, 1906; Serial No. 344,526.

To all whom it may concern:

Be it known that I, WILLIAM C. STEWART, a subject of the King of Great Britain, and a resident of Lynn, county of Essex, State of 5 Massachusetts, have invented an Improvement in Boot and Shoe Soles, of which the following description, in connection with the accompanying drawings, is a specification, like letters on the drawings representing like 10 parts.

This invention aims to provide a novel and highly flexible or pliable sole for boots, shoes or other foot wear.

The nature of my invention will be best 15 understood from a description of one embodiment thereof selected for illustration herein and illustrated in the accompanying drawing.

In this drawing; Figure 1 is a plan view of 20 one face of an insole illustrating one embodiment of my invention; Fig. 2 a longitudinal section on the line 2—2, Fig. 1, showing in dotted lines a portion of the insole bent or flexed; and Fig. 3 a transverse section on the 25 line 3—3, Fig. 1, on an enlarged scale, showing in dotted lines the relation of the slitted portion of the insole to the marginal portion, when the insole is flexed.

In the particular embodiment of my invention selected for illustration herein, and shown in the drawing, the sole illustrated and marked S is what is commonly known as a welt insole, that is, an insole adapted for use in the manufacture of what is known as a 35 welt boot or shoe, it being understood, however, that my invention is not restricted to such a sole.

The sole illustrated is provided with a marginal shoulder 5 following approximately the outline of the sole and, within said shoulder a shoe channel 6 to receive the welt or inseam stitches that secure the upper or welt to the insole. Within the channel 6 and, in the vicinity of the fore part or ball 45 portion of the sole the latter is shown provided with a series of transverse slits, slashes, or incisions 7 shown as oblique (see Fig. 2) and extending from one surface of the sole through nearly to the opposite surface 50 thereof, leaving an unslitted portion of relatively slight thickness such as will readily flex or bend when in use. Preferably the oblique slits will overlap each other slightly,

as shown, thereby to reduce the thickness of the intervening portions. The slits preferably open toward the heel end of the sole 55 although excellent results may be had where they open oppositely or toward the toe. I have found, however, that the transverse slits or incisions are much less effective in 60 flexing the sole if the intervening portions near the ends thereof are permitted to remain joined integrally to the marginal or unslitted portion of the sole. This is particularly true in a welt sole, because of the necessity for providing a raised lip or shoulder 65 through which to pass the inseam stitches. To obviate this objection, my invention comprehends slitting the sole lengthwise at or adjacent the transverse slits or slashes, as for 70 instance, at 8, these lengthwise or longitudinal slits preferably extending from the same face of the sole as the transverse slits and, inwardly to the bottoms of the transverse slits. The effect of these intersecting or longitudinal slits or incisions in the sole shown is to leave the sole portions lying between 75 the transverse slits free to throw outwardly as indicated in dotted lines Fig. 2, when the sole is flexed or bent in use, thereby giving to 80 the sole the greatest flexibility or pliability possible to be derived from the transverse slits unrestrained by any tying or uniting of the intervening portions with the unslitted marginal portions of the sole. In the sole 85 shown these longitudinal slits or incisions extend at their bottoms also obliquely downward following in this respect the planes of the transverse slits forming, substantially, tongue or partially separated portions 9, the 90 effect being that the entire portion of the sole lying above each transverse slit, is left free or separated at its ends from the marginal portion of the sole.

Ordinarily it is sufficient to provide the 95 intersecting or longitudinal slits or incisions at the ends only of the transverse slits, but, if desired, the said intervening sole portions may be longitudinally slit at other points between their ends, as, for instance, as indicated at 10.

I have referred to the flexibility of the sole being secured by slitting or slashing it, but obviously my invention contemplates any method of providing the sole with lines or 105 planes of weakness as defined in the claims.

whether by slitting, slashing, scoring or otherwise to produce the desired effect.

While it is convenient to arrange the transverse and longitudinal slits as here indicated, yet obviously the directions thereof may be changed relatively or otherwise as desired without detracting or departing from my invention.

Having described my invention by means 10 of one embodiment thereof as an illustration of the same what I claim in addition thereto and desire to secure by Letters Patent of the United States is:—

1. A sole for boots and shoes provided with 15 a series of substantially transverse incisions extending inwardly obliquely to one surface of the sole and an additional series of incisions angularly disposed with relation to the first series and laterally separated.

20 2. A sole for boots and shoes having a series of transversely extending incisions disposed obliquely to the surface of the sole, and a longitudinal incision at each side of the center of the sole, said longitudinal incisions being disposed in planes intersecting the planes 25 of said transverse incisions.

3. A sole for boots and shoes having substantially transverse incisions of less length than the width of the sole, and longitudinal 30 incisions disposed in planes intersecting the planes of said transverse incisions adjacent the terminal portions thereof.

4. A sole for boots and shoes having substantially transverse incisions disposed obliquely to the surface of the sole, a portion of 35 one transverse incision overlapping a portion

of another, and longitudinal incisions intersecting the transverse incisions.

5. A sole for boots and shoes characterized by substantially transverse incisions extending 40 partially across the sole forming transverse portions separated from the sole at one edge, said transverse portions each having terminal parts separated from the sole and forming integral tongues. 45

6. A sole for boots and shoes characterized by substantially transverse incisions disposed obliquely to the surface of the sole and forming transverse portions separated from the sole at one edge, terminal parts of said transverse portions being also free from the sole material. 50

7. A sole for boots and shoes incised transversely and obliquely with relation to the surface of the sole, and incised longitudinally 55 in planes intersecting the plane of the transverse incising and adjacent the terminal portions thereof.

8. A sole for boots and shoes provided with a series of transversely extending incisions disposed obliquely to the surface of the sole and opening toward the heel, and longitudinal incisions disposed in planes intersecting the planes of the transverse incisions. 60

In testimony whereof, I have signed my 65 name to this specification, in the presence of two subscribing witnesses.

WILLIAM C. STEWART.
